UNITED STATES PATENT OFFICE

107,044

DESIGN FOR A COFFEE PERCOLATOR

Samuel H. Geffner, Brooklyn, N. Y.

Application April 8, 1937, Serial No. 68,627

Term of patent 7 years

To all whom it may concern:

Be it known that I, Samuel H. Geffner, a citizen of the United States, residing in the Borough of Brooklyn, in the county of Kings, city and State of New York, have invented a new, original, and ornamental Design for a Coffee Percolator, of which the following is a specification, reference being had to the accompanying drawing, forming part thereof.

The figure on the drawing is an elevational perspective view of a coffee percolator embodying the new design.

The design, in addition to the features not specifically described but appearing on the drawing, consists particularly in the association of a pair of containers, one of which is transparent and lipped, with a cover having a handle disposed on the topmost one, and the containers each having a handle, one of the handles having a single freely extending body portion, as shown.

I claim:

The ornamental design for a coffee percolator, as shown and described.

SAMUEL H. GEFFNER.
